WELDER'S HOOD

Frank D. Ralston, Seattle, Wash.

Application October 27, 1944, Serial No. 560,599

3 Claims. (Cl. 2-8)

1

This invention relates to a welder's hood.

The primary object of this invention is the provision of an improved welder's hood preferably constructed of soft, flexible material, such as leather, providing features of comfort and utility to the wearer not hitherto known.

A further important object of this invention is the provision in a welder's hood of means to preclude the frosting over of the window thereof, such as might be occasioned by the breath of the user.

An additional important object is the provision of means in association with a welder's helmet which completely surrounds the head, whereby the wearer thereof may breathe comfortably and naturally without danger of inhaling particles or fumes given off by the welding arc.

Still another object is the provision of a welder's hood which may be readily retained in position at all times regardless of the position of the wearer thereof.

A still further object is the provision of a flexible welder's helmet which completely surrounds the head of the user and protects and covers completely areas of otherwise exposed skin, thus protecting the wearer not only from his own arc but from the arc of adjacent welders as well.

Still another object is the provision of such a helmet which may be readily adapted to various sizes of heads, in such manner to be worn with the maximum of comfort and efficiency.

Still other objects reside in the combination of elements and arrangement of parts and features of construction, all as will be more fully pointed out hereinafter and disclosed in the accompanying drawings wherein there is shown a preferred embodiment of this inventive concept.

In the drawings—

Figure 1 is a front elevational view of one form of helmet embodying features of this inventive concept.

Figure 2 is a fragmentary elevational view of certain features of the helmet disclosed in Figure 1 as seen from the interior of the helmet.

Figure 3 is a sectional view taken substantially along the line 3—3 of Figure 1 viewed in the direction indicated by the arrows, the flap being omitted in this view and

Figure 4 is an enlarged rear elevational view of the constructional details adapted for adjusting the size of the helmet, parts being broken away and omitted.

Like reference numerals refer to like parts throughout the several views of the drawings.

Having particular reference now to the draw-

2

ings, there is generally indicated at 10 a welder's helmet, preferably constructed of heavy, relatively pliable material, such as leather, and provided with a front skirt 11 and a rear skirt 12, adapted to depend well downwardly about the neck and over the chest and back of the wearer thereof.

The helmet is provided with an eye piece generally indicated at 13, consisting of a relatively heavy rectangular frame 14 secured in an aperture at the front of the helmet 10. The frame 14 has an interiorly positioned pane of clear glass 15 adjacent the helmet and has an extending portion 16 hinged as by hinges 17 to the frame member 14. The member 16 has positioned therewithin a pane of relatively dark glass 18 adapted to protect the eyes of the welder from the glare and ultraviolet rays emanating from the welding torch. A spring 19 positioned back of darkened glass pane 18 is adapted to secure the parts in related assembly. As best shown in Figure 1, extending portion 16 of frame 14 is provided with finger grips 20 whereby the frame may be raised to provide clear vision through the interior pane 15 when the device is not in use. A soft leather flap 21 fits as at 22 in front of helmet 10 and is adapted to overlie and protect the hinges 17 against damage or injury from molten metal or the like thrown off by the welding torch.

The helmet is adapted to be supported in such manner that the weight of the frame 14 does not bear against the wearer's nose, as by means of a roll 25, of sponge rubber, soft leather, upholstery webbing or the like, which is adapted to rest against the forehead of the user directly above the eyes and support the weight of the frame and its associated glass pieces.

Hitherto one common difficulty with welder's helmets has been the fact that the breath of the operator has a tendency to rise upwardly and cloud over the glass eye plate. This difficulty is overcome in the instant invention by the insertion of a sheet or piece 26 of fleece, soft leather, sponge rubber, or the like, secured at an edge, as at 27, peripherally about the front of the helmet 10 and adapted, through its natural resiliency to flare inwardly against the face of the operator, above the nose and mouth but below the eyes, in such manner that vision through the eye piece is unimpaired but the passage of breath from the nostrils or mouth upwardly to the eye piece is substantially precluded.

Means are also provided to facilitate the breathing of the wearer of the helmet, in such manner as to preclude the ingress of flame or

particles thrown out by the welding arc. Such means take the form of a channel or tunnel 30 comprised of relatively stiff leather, of a consistency sufficient to maintain its shape, and secured as at 31 and 32 (see Figure 3) adjacent a plurality of openings or apertures 34 in the front wall of the helmet adapted to be positioned in front of the mouth and nostrils of the wearer. The tunnel 30 is adapted to extend circumferentially about approximately half of the helmet and is open at both its rear ends, whereby air may pass from the rear of the wearer through the tunnel to the mouth and nostrils.

Chin straps 35 and 36 (see Figure 2), adapted to be secured together as by a buckle 37, are 15 suitably secured within the helmet adapted to be passed about the chin of the user in such manner that disalignment of the helmet, when the welder changes position, that is to say, moves his head out of the vertical for any reason, is precluded.

Means are also provided for adjusting the size of the helmet to conform to a variety of head sizes of operators. Such means take the form of a gusset 40 positioned at the rear of the helmet, and having two oppositely disposed flange-like members 41 apertured as at 42, and adapted to be secured in related assembly as by laces 43. Obviously, tightening or loosening of the laces 43 will vary the head size of the helmet.

Now, from the foregoing, it will be seen that there is herein provided a pliable, flexible welder's helmet, provided with improved means for precluding the clouding of the eye piece due to the user's breath, having improved mechanism to facilitate the breathing of the wearer, adjustable to a variety of sizes, and adapted to be relatively firmly secured in position, which accomplishes all of the objects of this invention and others, including many advantages of great practical utility and commercial importance.

As many embodiments may be made of this inventive concept, and as many modifications may be made in the embodiment hereinbefore set forth and described, it is to be understood

that all matter herein is to be interpreted merely as illustrative and not in a limiting sense.

I claim:

1. In a device of the character described in combination, a flexible hood, an eye piece therein, a member secured to the interior of said hood adapted to deflect the breath of the wearer from said eye piece, an aperture in said hood below said member, and a channel member peripherally positioned about said hood and communicating with said aperture, and opening at the rear of said hood.

2. A helmet comprising a flexible hood having an eye piece, an aperture in said hood below said eye piece, a flexible member providing an air passage secured upon the exterior of said hood, the ends of said passage being directed rearwardly of said helmet and being in communication with the atmosphere, an intermediate portion of said flexible member covering said aperture and said passage having communication therewith.

3. A welder's helmet including a hood having an eye piece and an opening in said hood below said eye piece, a conduit communicating with said opening and with the atmosphere at a point remote from said opening and a sealing means secured to and extending transversely of said hood between said eye piece and said opening for yieldingly engaging the face of the wearer and preventing direct communication in said helmet between said opening and said eye piece.

FRANK D. RALSTON.
